UNITED STATES PATENT OFFICE.

JOSEPH BEZARK, OF CHICAGO, ILLINOIS, ASSIGNOR TO MARSHALL FIELD & COMPANY,
OF CHICAGO, ILLINOIS, A CORPORATION OF ILLINOIS.

DESIGN FOR A COMBINED SAND BOX AND PLAY TABLE.

Application filed July 12, 1926. Serial No. 18,323. Term of patent 7 years.

To all whom it may concern:

Be it known that I, JOSEPH BEZARK, a citizen of the United States, residing at Chicago, in the county of Cook and State of Illinois, have invented a new, original, and ornamental Design for a Combined Sand Box and Play Table, of which the following is a specification.

The accompanying drawing, forming part of this specification, illustrates in perspective view a combined sand box and play table embodying my new design.

I claim:

The ornamental design of a combined sand box and play table, as shown.

JOSEPH BEZARK.
